THOMAS L. WANDS,

By B. D. Miller

Attorney

UNITED STATES PATENT OFFICE.

THOMAS L. WANDS, OF SPENCER, NORTH CAROLINA.

CLOTHES-TREATING APPLIANCE.

Application filed October 26, 1926. Serial No. 144,306.

My invention relates to clothes treating appliances.

In accordance with my invention, I provide a combined coat hanger and trouser presser and stretcher. The arrangement of parts is such that the presser is suspended from the coat hanger. The several elements constituting the invention are readily detachable and separable and the parts thereof, 10 are, therefore, adapted to be separated and collapsed. The construction is simple and the device has a high degree of utility.

In the accompanying drawings, forming a part of this specification, and in which like numerals are employed to designate like parts throughout the same,

Figure 1 is a side elevation of the apparatus embodying my invention,

Figure 2 is a similar view of the opposite side of the apparatus,

Figure 3 is an edge elevation of the same,

Figure 4 is a horizontal section taken on line 4—4 of Figure 2,

Figure 5 is an enlarged longitudinal section taken on line 5—5 of Figure 2,

Figure 6 is a fragmentary transverse section, upon an enlarged scale, which may be taken on line 6—6 of Figure 2,

Figure 7 is a perspective view of the stretching element and associated elements, and,

Figure 8 is a perspective view of the strips included in the trouser presser, showing the same collapsed.

In the drawings, wherein for the purpose of illustration, is shown a preferred embodiment of my invention, the numeral 10 designates a trouser presser, as a whole. This presser embodies a pair of companion strips 11, which may be formed of wood or the like, and these strips are permanently connected at their inner edges by means of hinges 12 or the like. The strips 11 are preferably covered upon their inner sides by means of a continuous liner 13, formed of cardboard or the like and this liner passes over the adjacent edges of the strips 11, and provides a continuous pressing surface, as clearly shown in Figure 4. Adapted to be 50 arranged opposite the strips 11 is a pair of pressing strips 14, which are connected at

their inner edges by means of hinges 15, such inner edges being spaced for providing a longitudinal opening or passage 16, as shown. The strips 14 are provided upon 55 their inner front faces with liners 17, which are separate, and are attached to the inner faces of these strips. The inner portions of the liners 17 extend over and across the passage 16 and substantially cover the same. 60 The liners 17 may be formed of cardboard or the like and are suitably stiff and relatively flexible. By the provision of the passage 16 and the flexible liners 17, the outer seam of the trouser legs will not be engaged 65 between the pressing faces of the strips, which would prevent the proper pressing of the edges or creases in the trousers. The edges of the liners 17 are readily flexed outwardly, as clearly indicated at Figure 6. 70

The two sets of pressing strips are permanently secured together and for this purpose one strip 14 is connected with the adjacent strip 11 by means of hinges 18. The leaves of these hinges fit within recesses cut in the 75 liners 13 and 17 and are flush with the surfaces thereof, whereby a flat surface is employed to press the trousers.

Secured to the strips 11 near their upper and lower ends are headed elements or studs 19, adapted to be received within key-hole openings 20 formed in transverse clamping straps 21. These transverse clamping straps are, therefore, detachably connected with the pressing strips 11. Arranged upon the 80 pressing strips 14, Figure 2, near their upper and lower ends, are headed studs 22, rigidly attached thereto, and adapted for insertion within key-hole openings 23, formed in clamping straps 24, as shown. These clamping straps 24, are, therefore, detachably connected with the strips 14 and may be separated from the headed studs by shifting the straps longitudinally with relation thereto. The straps 21 have hinged connections, at 85 their ends, as shown at 25, with transverse clamping bolts 26, the free ends of which are adapted for insertion within slots 27, formed in the ends of the clamping straps 24. The bolts 26 have their free ends screw-threaded 90 for receiving thumb-nuts 28.

The strips 11 are provided adjacent to

their upper ends with a transverse set of headed studs 29, for insertion within key-hole openings 30, formed in a transverse strap 31. This strap is, therefore, detachably connected with the strips 11 and its ends project beyond the outer edges of these strips and have hinged connections with transverse clamping bolts 32, as shown at 33. These clamping bolts carry thumb-nuts 34. The free ends of these bolts 32 are adapted for insertion within slots 35, formed in a metal strap 36, attached to cuff pressing strips 37, by means of screws 38 or the like. The strips 37 are spaced at their inner ends, affording a passage 39 therebetween, for receiving the outer seam of the cuff. The sections 37 have their inner faces covered by a continuous liner 40, formed of cardboard or the like which may be attached to the strips 37 by any suitable means. This liner is flexible and will, therefore, yield into the passage 39 as is obvious.

Operating in conjunction with the trouser presser is a stretching device, embodying a generally U-shaped pivotal support 41, the transverse portion 42 of which is slidably mounted within eyes 43, carried by leaves 44. These eyes are free to slide longitudinally upon the transverse portion 42 or to turn thereon. The leaves 44 are provided with transverse key-holes 45, for the reception of headed studs 46, preferably attached to the lower ends of the leaves 11, as clearly shown in Figure 1. It is obvious that the leaves are detachably secured to the strips 11. The stretching device embodies a trouser engaging clamp, including a stationary transverse jaw 47, having transverse openings to receive arms 48. The numeral 49 designates stops which rigidly engage the arms 48 and prevent the jaw 47 from moving inwardly upon the arms 48. The arms 48 extend outwardly beyond the jaw 47, as shown. The numeral 50 designates a co-acting jaw, embodying strips 51, preferably formed of wood and spaced at their inner ends for forming a passage 52. These strips are attached to the metal strap 53. One strip 51 and the strap 53 are provided at their outer ends with transverse apertures to pivotally receive the arm 48 and this arm is screw-threaded at its free end to receive a thumb-nut 54. The companion strip 51 and the opposite end of the strap 53 is provided with a transverse slot, to receive the other arm 48, also carrying a thumb-nut 54. It is obvious that the jaw 50 is brought toward the jaw 47 by manipulation of the thumb-nut 54.

It might be stated at this point that the upper or waist portion of the trousers is clamped between the jaws 47 and 50, and while the leg portions of the trousers are held between the strips 11 and 14, the trousers may be stretched longitudinally, by

swinging the stretching device upon the eyes 43 as pivots, as indicated in Figure 3. The stretching device may be maintained in this position by means of a chain 55, attached to one pressing strip 11 and arranged for detachable engagement with a hook 56, secured to the inner jaw 47. Instead of employing the chain 55, any other suitable flexible element may be employed, and I contemplate employing an elastic element, such as a spring. It is thus seen that the U-shaped pivot support 41 serves to carry the jaws 47 and 50 and to also connect with the strips 11, as shown.

Operating in conjunction with the trouser presser is a coat hanger 56, having a transverse rod 57. This rod slidably receives eyes 58, carried by leaves 59. These leaves are provided with a plurality of sets of key-hole openings 60 adapted for detachable engagement with headed studs 61, attached to the leaves 11. As clearly shown in Figure 3, the leaves 59 are L-shaped and hence offset forwardly. The coat may, therefore, be suspended from the coat hanger 56 and will lie entirely upon the side of the trouser presser, the inner side of the coat facing the trouser presser. This will eliminate the necessity of the coat receiving trouser presser.

In view of the foregoing description it is obvious that the several elements of the device are readily separable. The pressing strips 11 and 14 may be collapsed, after the removal of the transverse straps therefrom, as indicated in Figure 8. The remaining elements of the device, with the collapsed strips, may be readily assembled in a hand grip or the like.

In the use of the apparatus, the legs of the trousers are arranged between the pressing strips 11 and 14, with the inner seams adjacent to the passage 16. Suitable pressure is applied to the trouser legs by screwing up the thumb-nuts 54. The body and waist portion of the trouser is adapted to be held between the jaws 47 and 50, and the trousers are stretched longitudinally by turning the pivotal support member 38 upon its pivot, as explained.

It is to be understood that the form of my invention, herewith shown and described, is to be taken as a preferred example of the same, and that various changes in the shape, size and arrangement of parts, may be resorted to without departing from the spirit of my invention, or the scope of the subjoined claim.

Having thus described my invention, I claim:

In a clothes treating appliance, a trouser pressing device having a greater length than width, headed studs secured to the trouser pressing device at one end thereof, leaves provided with transverse keyhole openings

to receive the headed studs and adapted to be separated from the studs upon being shifted transversely of the trouser pressing device, said leaves having eyes, a U-shaped support embodying a transverse element pivoted within said eyes and carrying arms, a stationary jaw mounted upon said arms, a co-acting jaw pivoted upon one arm and having a transverse slot to receive the other arm and clamping nuts carried by the arms 10 to engage with the co-acting jaw.

In testimony whereof I affix my signature.

THOMAS L. WANDS.
